(57) CLAIM

The ornamental design for a heat sink for an illuminating device, as shown and described.

DESCRIPTION

FIG. 1 is a perspective view of a heat sink for a illuminating device showing our new design;

FIG. 2 is a front view thereof, the rear view being a mirror image of the front view;

FIG. 3 is a left side view thereof, the right side view being a mirror image of the left side view;

FIG. 4 is a top view thereof;

FIG. 5 is a bottom view thereof; and,

FIG. 6 is a reference view showing a state of being used thereof.

The broken lines shown in the drawings are for illustrative purposes only and form no part of the claimed design.
